FOREIGN PATENT DOCUMENTS

GB 6406159 * 12/2024

Primary Examiner — Sanjeev Paul

(57) **CLAIM**

The ornamental design for a quilt cover, as shown and described.

DESCRIPTION

FIG. 1 is a front and left side perspective view of a quilt cover, showing my new design;
 FIG. 2 is a top, rear and right side perspective view thereof;
 FIG. 3 is a front elevational view thereof;
 FIG. 4 is a rear elevational view thereof;
 FIG. 5 is a left side elevational view thereof;
 FIG. 6 is a right side elevational view thereof;
 FIG. 7 is a top plan view thereof;
 FIG. 8 is a bottom plan view thereof;
 FIG. 9 is a perspective view showing the quilt cover with the zipper close;
 FIG. 10 is an enlarged view of portion 10 in FIG. 1;
 FIG. 11 is an enlarged view of portion 11 in FIG. 6; and,
 FIG. 12 is an enlarged view of portion 12 in FIG. 7.
 The dash-dot-dash broken lines define the boundary of enlarged views and form no part of the claimed design.
